(57) **CLAIM**

I claim the ornamental design for a pillow, as shown and described.

DESCRIPTION

FIG. 1 is a back-bottom perspective view of a pillow of the present invention.

FIG. 2 is a back elevation view thereof.

FIG. 3 is a front elevation view thereof.

FIG. 4 is a right side elevation view thereof, the left side elevation view being a mirror image of the right side elevation view.

FIG. 5 is a top plan view thereof.

FIG. 6 is a bottom plan view thereof; and,

FIG. 7 is a back elevation view thereof showing the pillow relative to a hand and an arm connected to the hand for holding the pillow against the head.

The dashed lines depict portions of the pillow that form no part of the claimed design. The dot-dash lines depict visible portions of an arm or hand; the arm and hand represent the operating environment and form no part of the claimed design.
